UNITED STATES PATENT OFFICE.

CHARLES L. LEE, OF DAYTON, OHIO, ASSIGNOR TO GENERAL MOTORS RESEARCH CORPORATION, OF DAYTON, OHIO, A CORPORATION OF DELAWARE.

FURNACE.

Application filed July 3, 1922. Serial No. 572,504.

To all whom it may concern:

Be it known that I, CHARLES L. LEE, a citizen of the United States of America, residing at Dayton, county of Montgomery, 6 and State of Ohio, have invented certain new and useful Improvements in Furnaces, of which the following is a full, clear, and exact description.

This invention relates to furnaces for 10 brazing cooling fins to iron or steel bodies, and more particularly to furnaces for attaching copper fins to iron cylinders of internal combustion engines.

In the preferred embodiment of the present 15 invention the furnace is constructed and arranged to carry out the process of cylinder construction claimed and described in the copending application of Charles F. Kettering, Serial No. 514014, filed November 9, 1921, and in the present invention the 20 form disclosed constitutes improvements in the apparatus described and claimed in my copending application, Serial No. 396, 276, filed July 14, 1920.

In my copending application there is disclosed a furnace which includes a liquid fuel burner having a combustion tube extending out from the igniting chamber of the burner, and there is a furnace shell rotatably mounted co-axially with the burner 30 combustion tube. The products of combustion in the burner are directed into the inside of a cylinder of cast iron or steel having its head closed and having its opposite end open and connected with a burner stack but sealed off from the space within the furnace shell which surrounds the outside of the cylinder. Before placing the cylinder in the furnace shell a strip of brazing brass is placed around the outside of the cylinder and a strip of fin loops is placed 40 around the cylinder wall and on the outside of the brazing brass. The fin material and the brazing strap are held in position by 45 means of iron binding wires. While the cylinder is being heated from the inside the cylinder is rotated in order to secure uniform heating and so that the brazing brass will be uniformly distributed when the furnace 50 temperature is such as to melt the

brass but not the fin material. After the brazing temperature has been reached and the brass is melted, the burner is turned off but the furnace shell is rotated so that on cooling the brazing brass will be uniformly 55 distributed and will fill up all the spaces between the fin material and the cylinder shell. This cooling may take several minutes, after which rotation is stopped, the furnace is opened, the cylinder removed 60 and another cylinder assembly to be brazed is inserted. In this apparatus the turning off of the burner and the stopping of the furnace shell are entirely within the control 65 of the operator.

Among the objects of the present invention is to render the steps above mentioned more or less automatic in character and with this in view means has been provided for automatically controlling the heating and 70 cooling of the cylinder assemblies; other means has been provided enabling the insertion and removal of the cylinder assemblies with greater rapidity and ease; and means has also been provided to enable a 75 number of furnaces to be operated simultaneously; all of these means together with other features not mentioned tending to greatly increase the output and uniform high quality of the product. 80

Further objects and advantages of the present invention will be apparent from the following description, reference being had to the accompanying drawings, wherein preferred forms of embodiments of the present 85 invention are clearly shown.

In the drawings:

Fig. 1 is a plan view of a furnace bank of three furnaces, showing the furnace shells in different positions; 90

Fig. 2 is a side elevation of one of the furnaces disclosed in the bank shown in Fig. 1;

Fig. 2^a is a plan view, partly in section, of a frame or housing member for supporting the controlling apparatus of a bank 95 of furnaces.

Fig. 18 is an end view of the controlling magnet taken in the direction of arrow 18 40 in Fig. 15;

Fig. 19 is a sectional view taken on the line 19—19 of Fig. 15;

Fig. 20 is a sectional view on an enlarged scale of the furnace controlling mechanism, this view being taken approximately on the line 20—20 of Fig. 1;

Fig. 21 is a sectional view taken on the line 21—21 of Fig. 20;

Fig. 22 is a sectional view taken on the line 22—22 of Fig. 20;

Fig. 23 is a view similar to Fig. 22 but showing the parts in a different position;

Fig. 24 is a sectional view taken on the line 24—24 of Fig. 20;

Fig. 25 is a view similar to Fig. 24 but showing the parts in a different position;

Fig. 26 is a view showing certain parts shown in Fig. 21;

Fig. 27 is a fragmentary view partly in section showing the installation of a thermo-couple or other temperature responsive device;

Fig. 28 is a view looking in the direction

of the arrow 28 of Fig. 27, certain parts being broken away to show the interior structure;

Fig. 29 is a wiring diagram of the electrical equipment for the furnace, also a diagrammatic showing of a motor driven 70 air compressor for the furnace burners;

Fig. 30 is a plan view with the cover removed of a fuel supply tank; and

Fig. 31 is a sectional view taken on the line 31—31 of Fig. 30. 75

In the drawings numeral 50 (Fig. 1) designates the bank of furnaces comprising three furnaces units each designated as a whole by numeral 51. Referring now to Fig. 2, unit 51 comprises a frame 52 having 80 a track 53 upon which rolls a furnace shell bracket 54 which supports a furnace shell 55. Frame 52 supports a controller frame or housing 56 upon which is mounted a burner designated as a whole by the numeral 85 57.

The furnace shell and supporting bracket will first be described. The bracket 54 includes a side web 60 (Fig. 7) and a connecting cross web 61, these webs merging into 90 a neck 62 which connects with a hub 63 providing a bearing for the loosely journalled furnace shell shaft 64. (See Figs. 7 and 27.) The webs 60 are connected by pins 65 and 66 on which are journalled rollers 67 and 68 95 respectively which are adapted to roll on the track 53. The frame 52 is provided with a curved end portion 69 so formed that the roller 68 may swing around the underside of this curved portion and may strike a stop portion 70. The webs 60 are also connected by a pin 71 having fixed thereon a stop member 72 provided with a finger 73 which may slide along within a groove 74 which extends below the surface of the track 53. The finger 73 is adapted to strike against a stop plate 75 located at the bottom end of the groove 74. Bracket 54 carries a roller 76 adapted to strike against the arcuate surface 77 of the shock lever 78 which is pivoted at 79 upon 100 the frame 52. 105

Bracket 54 also carries a roller 80 adapted to strike against the concave curved surface 81 of the lever 78. Lever 78 has a pivotal connection at 82 with a rod 83 which passes through a collar 84 having a stem 85 by means of which said collar 84 is pivoted upon the frame 52. Rod 83 carries nuts 86 and a washer 87, and a spring 88 is located between the collar 84 and the washer 87 115 and this spring 88 normally holds the lever 78 in position shown in Fig. 5. The pin 71 serves to attach the bracket 54 to the yoke 89 of a link 90 having yoke 91 straddling the leg 92 of frame 52 and connected by pin 93 with arms 94 located on each side of frame 52 and pivoted on pin 95 carried by 120 the frame. A slot 96, concentrically ar- 125

ranged with the pin 95, carried by the frame 52, is provided in said frame. This slot is adapted to receive the pin 93 of the lever 91, whereby the movement of said lever is limited to the length of the slot.

The bracket 54 is provided with a stop 100 adapted to engage a throw out lever 101 pivoted at 102 upon frame 52 and having a lug 103 adapted to engage a stop 104 carried by frame 52. A spring 105 attached at 106 to frame 52 and at 107 to the lever 101 tends normally to maintain the lever 101 in the position shown in Fig. 2 or to maintain the lever 101 in contact with the stop 100 when the parts are in the position in Fig. 5. Referring to Fig. 13 bracket 54 carries a latch plate 110 having a notch 111 adapted to be engaged by latch lever 112 pivoted at 113 upon a bracket 114 extending out from the controller housing 56. A mechanism for operating the latch lever 112 will be described later. For the present it is sufficient to state that there is mechanism for rotating the latch lever 112 clockwise so that the latch plate 110 may be released. The latch lever 112 is held normally in position shown in Figs. 13 and 20, by means of a spring 115 attached at 116 to the lever 112 and the other end is attached to the frame 52. When the bracket 54 is moved toward the burner the beveled surface 118 provided on the latch plate 110 will strike the beveled surface 119 provided on the lever 112 causing the lever 112 to be moved clockwise as viewed in Fig. 13 until the hooked portion of the lever will ride over the top of latch plate 110 and will snap into the notch 111 thus locking the bracket 54 in operative position.

The shaft 64 which rotatably supports the furnace shell is provided with a flange 120 Fig. 27 to which is attached by screws 121 a ring 122 provided with side holes 123 to assist in dissipating heat. To this ring 122 is bolted furnace shell 55 by means of screws 125. Shell 55 at its open end is provided with an annular recess 126 Fig. 9 adapted to receive the annular flange 127 of the furnace shell cover 128 which is provided with the circular flange 129 which contacts with trunnions to be described, by means of which rotation is imparted to the furnace shell and cover. The shell 55 is provided with lugs 130 and 131 which support pins 132 and 132^a respectively. Pin 132 carries a latch lever 133 having a handle 134 and an arcuate notch 135 adapted to receive a pin 136 supported by lugs 137 extending from the shell cover 128. The pin 132^a supports a latch lever 133^a, and a notch 135 of this lever is adapted to receive a pin 138 attached to links 139 having at one end round holes through which pass a pin 140 which is supported by lugs 141 extending from the shell cover 128. The lugs 131 are

provided with slots 142 to permit of movement of the pin 140 relative to the furnace shell 55. The links 139 are provided with slots 143 through which the pin 132^a extends, said slots 143 permitting movement of the links 139 relative to the furnace shell 55. The latch lever 133^a is located between the links 139 as shown in Fig. 12, and is attached to the pin 132^a. The handle 134^a is also attached to the pin 132^a so that by moving the handle 134^a the latch 133^a will be operated. It is apparent therefore that when the furnace shell has been removed to the position shown in Fig. 2, the shell cover 128 may be lifted upwardly after the latch levers 133 and 133^a have been moved to the position shown in Fig. 11 and the cover 128 may be swung in the position shown in Fig. 14 with the lugs 141 resting against pins 144 carried by the lugs 131.

In Fig. 9, a shell 55 is provided with a cylindrical refractory lining member 150 with an end lining member 151. Likewise cover 128 is provided with a cylindrical lining member 152 and with an end lining member 153. The end wall of shell 55 carries a stop member 154 against which rests the head 155 of a cylinder 156 having side walls 157 and a rectangular base or mounting flange 158. The cylinder head 155 which is illustrated by way of example, includes intake and exhaust passages and is provided with mounting flanges 159 and 160, faces of which are machined or parallel to one another and to the axis of the cylinder. These flanges assist in locating the cylinder within the furnace shell. As shown in Fig. 9 the flange 159 rests against a clamp member 161 attached to the shell 55 by means of bolts 162 and nuts 163. The flange 160 of the cylinder head 155 rests against a movable clamping member 164 which is carried upon a plunger 165 which slides through the furnace shell 55 and is also guided by a yoke 166 attached by screws 167 to the furnace shell. A spring 168 located between the yoke 166 and a collar 169 pinned at 170 to the plunger 165, serves to maintain the clamp 164 against the flange 160.

The furnace cover 128 is provided with a mounting block 171 having a central opening 172 and a rectangular recess 173 adapted to receive the cylinder flange 158. The central hole 172 Fig. 14 is in alignment with similar holes provided in the lining member 153 in the head of the cover 128, which holes are co-axial with a collar member 175. When the cover 128 is clamped by means of the clamping lever 133 in position upon the shell 55 as shown in Fig. 9 the cylinder 156 will be clamped between the mounting blocks 171 and 154 while the clamping members 161 and 164 assist in maintaining the cylinder 156 substantially concentric to the furnace shell. A fin material is indicated at 176 and the

binding wires at 177. For further description of the method of assembling the fin material and brazing matter upon the cylinder 156 reference is made to the copending 5 application of Charles F. Kettering referred to.

The burner 57 will next be described. This burner includes a base 180 having a dove-tail portion 181 adapted to be received 10 by guide 182 and a gib 183 included between said dove-tail 181 and guide 184. These guides 182 and 184 are formed integrally with the upper surface of the controller housing 56. By virtue of this construction the burner bracket 180 is adjustable with respect to the furnace shell 55. The bracket 180 supports a burner housing 185 having a mounting flange 185^a. The body 185 supports a burner insert 186 carrying an 15 atomizing orifice 187 and a fuel nozzle 188. Nozzle 188 is attached to a fitting 189 supported by the burner housing 185. Body 185 is provided with a fitting 190^a attached to air hose 190. Air delivered from the hose 190 20 will pass through the orifice 187 and cause fuel to be sucked up from the nozzle 188 and to be sprayed out into the insert 186. This spray is ignited by a spark from the spark plug 191 and mixes with air coming in 25 through the small holes 192 in the wall of the insert 186. As air is supplied to the burner under pressure a flame will be projected out through the flame tube 193 which is supported by means of a flame tube 30 bracket 194 having a mounting flange 195 attached by screws 196 to the mounting flange 185^a of burner 185. The products of combustion from this flame tube 193 will be delivered into the interior of the cylinder 35 156, and since the exterior of this cylinder is sealed off by the cylinder mounting members from the interior of the furnace the combustion products will pass from the cylinder 156 back through the tubular extension 197 of the flame tube bracket 194 40 and out through a stack 198. The flame tube 193 being subjected to high temperature will require replacement before other parts of the burner are worn out. This tube is constructed preferably of metal which is not 45 readily deteriorated by heat but in order to facilitate replacement this tube is detachably secured in position by means of a set screw 199. A leveling screw 200 has a screw 50 threaded connection with the bracket 180 and is locked in position by a lock nut 201. This screw 200 assists in supporting the combustion tube bracket 194.

The furnace operating and controlling 55 mechanism supported by the controller housing 56 will now be described. In Figs. 20 to 25 a housing 56 is provided with a bearing 210 and with a cover 211 having a bearing 212. Bearing 210 supports a 60 sleeve 213 in which is journalled a shaft 214

which is also journalled within the bearing 212. The shaft 214 loosely supports a worm gear 215 meshing with a worm 216 (see Fig. 21) which is carried upon a shaft 217 which extends through all of the furnace controllers in a bank of furnaces. Each of the controller housings 56 carries a bracket 218 providing a journal for this shaft. Within each of the housings 56 the shaft 217 carries a beveled gear 219 meshing with a beveled gear 220 carried by shaft 221 journalled within the bearing 222 supported by bearing bracket 223 formed integrally with the housing 56. Each shaft 221 extends through the end wall of the 70 housing 56 and is supported by a bracket 225 and carries a trunnion 226 having a beveled edge 227. Outside of the controller housing 56 the shaft 217 carries beveled gears 228 each meshing with a beveled gear 229, each carried by a shaft 230, each shaft 230 being supported by brackets 231 and 232 and carrying trunnions 226. Each pair of trunnions 226 is adapted to receive the flange 129 of the furnace shell cover 128. 75

The three housings 56 support controlling devices for the bank of three furnaces shown in Fig. 1 and are preferably tied together by web members 233 so that the rear ends of all the frames 52 are tied together 80 by one casting. Other tie members 234 which are bolted to mounting pads 235 (see Fig. 5) serve to attach the frames 52 together. A motor supporting shelf 236 which is supported by two of the housings 85 56 carries an electric motor 237 which drives a shaft 217 through a train of gears located in a gear box 237^a. The motor 237 also drives a timer distributor element 238 for supplying ignition sparks intermittently 90 through the high tension cables 239 to the burner spark plugs 191.

Each shaft 214 supports a worm gear 215 carrying a cam 250 provided with a cam slot 251, ratchet 252 to which are pinned cams 253 and 254, air valve cam 255 and furnace rotation timing cam including relatively adjustable members 256 and 257. Member 256 is pinned to the shaft 214 while the member 257 is carried on the sleeve 213 which has keyed thereto a collar 258 carrying graduations 259. A collar 260 is keyed to the shaft 214 and by tightening up on the nut 261 which is rotated on the shaft 214, the sleeve 213 carrying the cam member 257 will be clamped between the cam member 256 and the collar 260. Therefore by loosening the nut 261 the sleeve 213 may be rotated relative to the shaft 214 by turning the graduated collar 258. Relative movement between the cam members 256 and 257 is limited by pin 262 which projects through an arcuate slot 263 carried by the cam member 256. The shaft 214 is connected with an operating rod 264 by means of universal 100 105 110 115 120 125 130

joint 265. The rod 264 is supported by bracket 266 carried by frame 52 and is provided with a handle 267.

The bracket 218 supports a stud 270 upon 5 which is journalled a lever 271 carrying cam roller 272 which projects into cam slot 251. A pawl 273 carrying a pin 274 is pivotally mounted at 275 upon the lever 271 and a spring 276, located between the stud 277 10 carried by lever 271 and the pawl 273, normally maintains the pawl 273 in contact with the ratchet 252. The bracket 218 carries a pin 280 against which bears a spring 281 bearing also against a pawl 282 pivotally mounted at 283 on the bracket 218. Pawl 282 cooperates with the ratchet 252 to prevent backing up of the ratchet.

The stud 270 supports an escapement lever 290 having teeth 291 and 292 so related to 20 the cams 253 and 254 that after the cam 253 has been turned far enough to clear the tooth 291 there will still be a slight amount of clearance between the cam 254 and the tooth 292 so that by gravity the lever 290 25 may drop from the position shown in Fig. 25 to the position shown in Fig. 24. The lever 290 has an extension 293 adapted to engage with the pin 274 whereby to throw the pawl 273 out of engagement with ratchet 30 252 when the lever 290 occupies the position shown in Fig. 25.

The cam 255 is adapted to engage a lever 300 journalled upon a stud 301 carried by the housing 56. Lever 300 is connected to link 302 which extends up through a hole 303 provided in the top wall of the housing 56 and connected at 304 with a lever 305 which is pivoted at 306 upon a valve casting 307 secured by bolts 308 to the top of housing 40 56. Casting 307 is provided with an intake passage 309 communicating with air delivery pipe 310. Pipe 309 leads through a valve seat 311 to an outlet passage 312 being adapted to receive air hose 190 leading to the fuel burner 57. The valve seat 311 receives a valve 313 having a stem 314 passing through packing material 315 and a packing gland 316. A spring 317 interposed between the valve 313 and located within a recess in the 45 head of the valve bears against a plug 318, this spring 317 normally maintaining the valve 313 upon its seat. When the cam 255 is turned clockwise as viewed in Fig. 19, the lobe 255^a will strike against the projection 300^a of the lever 300 causing the link 302 to move up and the lever 305 to open the valve 313. As long as the projection 300^a rests on top of the lobe 255^a this valve will 50 be held open, therefore this cam constitutes a member for initially opening the air valve. Since it is desirable to cause the air valve to be closed in accordance with the temperature within the furnace and independent of the 55 operation of the shaft 214 other means are provided for holding the valve open after

the cam lobe 255^a has moved away from the projection 300^a. This means includes a pin 320 which is carried by the lever 305 and is arranged to rest upon a finger 321 carried upon the shaft 322 which is supported by 70 bracket 323 mounted upon the housing 56. The shaft 322 carries an arm 324 provided with a slotted portion 325 with which cooperates a pin 326 carried by a fork 327 mounted upon the end of a rod 328 attached to a 75 solenoid armature 329. Armature 329 slides within a tube 330 surrounded by magnet winding 331 having terminals 332 and 333 and housed within a magnetizable tube 334 which is supported by bracket 335 upon the 80 bracket 323. A spring 336 interposed between bracket 335 and a washer 337 carried by the rod 328 normally presses the finger 321 toward the pin 320. As shown in Fig. 16 the magnet 331 has been energized sufficiently to attract the armature 329 toward a core portion 338 and to move the finger 321 out from under the pin 320. Fig. 16 shows the finger 321 on the verge of leaving the pin 320. As will be explained later the 90 winding 331 is responsive to temperature and when the desired temperature has been reached, this winding will be energized sufficiently to move the finger 321 away from the pin 320. In the normal operation of the 95 machine the cam lobe 255^a will have been moved away from the projection 300^a before the maximum temperature is reached. Therefore, if finger 321 releases the pin 320 the spring 317 will be free to close the valve 100 313 thereby stopping the burner by cutting off the supply of air and fuel.

In the wiring diagram shown in Fig. 29, the winding 331 is shown connected with current supply leads 340 and 341 by means of a main switch 342 and a relay switch 343 which is controlled by a magnet winding 344, the terminals of which are attached to brushes 345 and 346 bearing against slit rings 347 and 348 respectively, these rings being connected with a thermocouple 349 which is located within the furnace shell 55 and subjected to the hottest temperature within the furnace. The thermocouple is mounted upon the sleeve 350 and the wires from this couple are connected with the slit rings 347 and 348 which are mounted as shown in Fig. 27 upon the furnace shaft 64 but insulated therefrom. The brushes 346 and 347 are mounted upon the housing 351 110 which is attached by screws 352 to the bracket 54. The housing 351 is provided with an end cover 353. By removing the cover 353 the leads from the thermocouple may be detached from the slit rings and the thermocouple withdrawn out through the open end of the furnace.

The supply means 340 and 341 are connected by switch 360 with the motor 237 which drives the timer-distributor 238. The 115 120 125 130

6 timer contacts 361 and 362 are connected with ignition coil primary 363 which is connected with battery 364. The ignition coil secondary 365 is connected with the center 5 terminal 366 of the distributor head, and from this terminal the sparking impulses are distributed in the usual well known manner to terminals 367, each connected by high tension wire 239 with a burner plug 191 shown 10 in Fig. 1.

In order to secure uniform fuel to the burners there is provided a constant level fuel tank 370 shown in Figs. 30 and 31 which has an inlet 371 leading from a source 15 of supply and an outlet 372 connected by a pipe 373 with all the burners of the bank of furnaces or even more depending upon the capacity of the tank 370 and inlet and outlet pipes. A float controlled valve 374 is mounted 20 upon an arm 375 pivoted upon a bracket 376. The arm 375 carries a float 377 so constructed as to maintain the fuel level as shown in Fig. 31 slightly above the valve seat 378. The source of supply of air pressure 25 for the burners is preferably an air compressor 380 driven by an electric motor 381 connected by a double pull switch 382 with the current supply leads 340 and 341. Compressor 380 is connected with a pressure 30 tank 383 carrying a gauge 384 and the outlet pipe 385 from the tank 383 leading to the various pipes 310 shown in Fig. 19 is controlled by a valve 386.

The operation of the apparatus is as follows:

Let it be assumed that the brazing operation has been completed and that the burner has been shut off automatically. The cam 257 is shown in Fig. 26 as rotated in a clockwise direction far enough so that the portion 257^a has pushed the roller 112^a which is carried by the lever 112 down so that this lever 112 will be rotated clockwise as viewed in Fig. 13 to clear the notch 111 and thereby 45 to release the latch plate 110. When this has occurred the spring 105 will operate through the push out lever 101 to move the bracket 54 away from the furnace so that the flange 129 will move off the trunnions 226 and rotation of the furnace will cease. The operator noticing that a furnace has stopped 50 rotating will know that the brazing operation has been completed and will pull the furnace into the position shown in Figs. 2 and 14. In Fig. 1 the furnace at the bottom 55 of the drawing is shown in this position. To move the furnace into this position the operator stands at the back of the furnace and grasps handle 54^a attached to shell carriage or bracket 54 and pulls the bracket 54 toward him. As the bracket 54 rolls along the rail 53 the roller 80 will roll along the concave surface 81 of the lever 78, and lever 60 78 will be rotated clockwise from the position shown in Fig. 5 to the position in Fig.

6. In Fig. 6, the roller 68 has just cleared the track 53 so that the bracket 54 may now be tilted. At the same time, the stop finger 73 shown in Fig. 7 has just engaged the stop plate 75, and the lever 78 has received the maximum movement due to the pressure from roller 80 and the spring has received the maximum additional stress due to this movement of lever 78.

The stop finger 73 and plate 75 constitute 75 a pivotal support for the bracket or carriage 54, about which the carriage load may be tilted. As the center of mass of the carriage load is swung upwardly, assistance is given by spring 88 acting through lever 78. 80 After the center of mass of the carriage load has swung to the right of the pivotal support provided by members 73 and 75, gravity will assist in the further tilting of the carriage. The fall of the furnace shell into 85 vertical position, due to its own weight is cushioned when the roller 76 strikes against the concave surface 77 of shock lever 78, causing the lever to be rotated again clockwise as viewed in Fig. 2 and the spring 88 90 to be compressed.

While the furnace shell is retracted the shock lever 78 receives two shocks. It requires a little exertion to start the carriage 95 into motion owing to the mass of the carriage and shell. The carriage load may acquire a considerable momentum if the carriage be retracted rapidly. Some of this momentum should be absorbed by other means than by stop members 73 and 75, and 100 this is done by the roller 80 engaging the concave surface 81 of lever 78 whereupon some energy is absorbed by spring 88 to be given out again in assisting in tilting the carriage and shell. The shock lever 78 and 105 spring 88 and related parts therefor constitute means for overcoming some of the momentum of the carriage load and for storing energy to be applied for the tilting operation.

The second shock occurs when the roller 76 strikes the lever 78 and momentum of the carriage load due to gravity acting thereon is absorbed again by spring 88 to be given out later in assisting the tilting of the 110 shell into horizontal position.

The weight of the furnace 55 is now partly carried by the spring 88 after the roller 66 (see Fig. 7) moves into engagement with the stop 70. The mass of the furnace which 115 overhangs to the right of the roller 76 tends to lift the pin 71 upwardly but this cannot occur because the yoke 90 would transmit upward pressure from the pin 71 to the pin 93 which bears in the position shown in 120 Fig. 2, against the upper end of the slot 96. The furnace cover 21 is thrown open and up into the position shown in Fig. 14. The completed cylinder assembly 156 is removed 125 and replaced by an assembly which has not 130

received the brazing operation. The cover is turned down again upon the furnace as shown in Fig. 2 and the clamping levers 133 and 133^a are turned up to clamp the 5 cover 128 upon the furnace shell 55 as shown in Figs. 2 and 10. The operator then grasps the handle 54^a and tilts the bracket 54 upon the track 53.

The tilting of the shell into horizontal 10 position is assisted first by the spring 88 acting through lever 78 and roller 76. After the center of mass of the carriage load has been tilted to the left of the pivotal support, as viewed in Fig. 2, then gravity will assist 15 in further tilting the carriage onto the track. The momentum of the carriage load as it falls toward the track is absorbed by the spring 88 upon the roller 80 striking the lever 78 on surface 81, whereupon spring 20 88 will again be additionally compressed. This additional energy thus stored in spring 88 is used in assisting to move the carriage toward the burner. Thus it is seen that during 25 the return movement of the shell into operative position, the shock lever cushions the fall of the carriage onto the track and causes the spring to store extra energy to assist in moving the carriage toward the burner.

The bracket 54 is moved toward the burner until the latch plate 110 is latched by the lever 112 as shown in Fig. 13, the shaft 214 having first been turned by the handle 267 until the graduated collar 259 registers 30 zero or home position. In this position the roller 112^a will occupy the position relative to the cam 256 shown in Fig. 26. In this position the roller 112^a is pulled against the cam 257 by means of the spring 115 shown 35 in Fig. 20 thus permitting the latch lever 112 to engage with the latch plate 110 and hold the furnace bracket 54 in operative position with the flange 129 engaging the trunnions 226.

The trunnions 226 are beveled as shown 40 at 227 in Fig. 20 in order that the flange 129 may slide up onto the cylindrical portion of the trunnion. As the flange 129 moves along the beveled surface of the trunnions 226 the greater portion of the weight 45 of the shell 55 is transferred from the bearing 63 to these trunnions. The shell rocks about the bearing 63 as a pivot, this rocking movement being permitted by making the 50 journal diameter of shaft 64 preferably about $\frac{1}{2}$ inch less in diameter than the internal diameter of bearing 63.

The turning of the shaft 214 into zero or 55 home position causes the cam 254 shown in Fig. 25 to engage with the finger 292 of the lever 290 just as the finger 281 clears the cam 253. Then the lever 290 will drop from the position shown in Fig. 24 60 into the position shown in Fig. 24 and the arm 293 will release the pin 274 carried by pawl 273. The pawl is then in operative position for intermittently moving the ratchet 252 in clockwise direction as viewed in Figs. 22 and 23. The cam 250 is being constantly rotated by the motor 70 through a gearing described at a rate of about one revolution per minute. Each revolution of the cam 250 causes the roller 272 and the arm 271 to move up and down across the face of the ratchet 252 and this 75 travel is such that the pawl 273 will be retracted and moved forward a distance a little greater than the pitch of the ratchet teeth, therefore the ratchet will be moved ahead one tooth space for each minute of 80 operation of the motor. When the lever 290 is in position shown in Fig. 24 the shaft 214 is free to rotate in a clockwise direction.

The turning of the shaft 214 in the home 85 position causes the cam lobe 255^a in Fig. 19 to move the projection 300^a upwardly thereby causing the air valve 313 to be opened. Air can then pass to the burner and cause 90 fuel to be sucked up from the fuel tank to the burner nozzle and sprayed out into the burner where the fuel mixture is ignited from the spark plug 191. The products of combustion of the burner pass out the tube 193, into the cylinder shell and then out 95 through the bracket 197 and the stack 198 as explained before and as stated in the co-pending application of Charles F. Kettering referred to, the combustion products of the burner do not come in contact with the outside of the cylinder and the fin material. 100 The heat travels from the interior of the cylinder walls and through the brazing brass into the fins from whence the heat is dissipated in heating up the interior of the furnace shell and cover. When the temperature 105 has increased to the desired amount within the furnace shell and outside of the cylinder assembly, which temperature is preferably 1750° Fahr. the temperature difference between the juncture and terminals of the 110 thermocouple 349 will be such that enough current will be produced to cause the magnet 344 to pull the switch 343 shown in Fig. 29 into closed position. Then current will flow 115 from the main leads 340 and 341, the switch 342 being closed, and magnet 331 will be energized causing the armature 329 to be sucked in. The finger 321 will be moved to the left as viewed in Fig. 16 releasing the stop pin 320. The average time required for 120 heating the furnace up to this temperature is known approximately, therefore, the opening of the cam lobes 255^a as shown in Fig. 19 is made short enough that this lobe will be 125 clear of the projection 300^a before the maximum in furnace temperature is reached. In other words if the time required to bring the smallest cylinder assembly treated by the furnace up to the maximum temperature be 10 minutes then it should require less than 130

this time to turn the shaft 214 from home position and to move the cam lobe 255^a so that it clears the projection 300^a as shown in Fig. 19. The time for cam lobe 255^a to clear 300^a is about five minutes where the return of travel of the ratchet is a distance of one tooth space per minute.

The operation of the magnet 331 to release the pin 320 shown in Fig. 16 permits the lever 300 to drop down and the spring 317 to close the valve 313. Therefore the burner will stop and the furnace will begin to cool. It is desirable to continue the rotation of the furnace for a few minutes after the maximum or cylinder brazing temperature has been reached. Therefore the cam portion 257^a shown in Fig. 26 is so related to the cam portion 256^a that the movement of the shaft 214 from home position which is required to bring the portion 257^a into engagement with the roller 112^a and to move the roller 112^a downwardly as viewed in Figs. 26 and 20 the full amount, will require a time which will be a few minutes greater than the time required for bringing the furnace up to the brazing temperature. For example, if the particular cylinder assembly being brazed requires 12 minutes before the maximum brazing temperature is reached then this time could be about 15 or 16 minutes. Therefore, the furnace will be rotated three or four minutes after the furnace starts to cool down. This is desirable in order that the brazing material which is in a molten condition at the maximum furnace temperature will be uniformly distributed while solidifying. When the roller 112^a has been cammed out on the lobe of the cam members 256, 257 the lever 112 will be rotated in a clockwise direction as viewed in Fig. 13 and the latch plate 110 will be released and the throwout lever 101 will move the furnace bracket 54 away from the burner and through a distance great enough so that the flange 129 will be clear of the trunnions 226.

The cycle of operations of the furnace has been completed. If the graduated collar 259 showed zero in the start of the burner operation then when the furnace bracket 54 was unlatched this collar would show the number of minutes between the start and the unlatching or in other words the number of minutes of furnace rotation. As the duration of furnace rotation depends upon the character and size of the cylinder being treated it is desirable to make this time variable. Therefore in changing this time to start a different cylinder the motor 237 should be stopped so that rotation of the shaft 214 will not continue. The nut 261 shown in Fig. 20 is loosened and the collar 260 drawn away from the graduated collar 258. This collar is turned so as to indicate the desired number of minutes of furnace rotation. If more time is required then the sleeve 213 con-

nected with the collar 258 is turned in a counter-clockwise direction as viewed in Fig. 26 so that there will be a greater distance between the cam portions 256^a and 257^a. The cams 256 and 257 are so constructed that when their edges coincide the maximum time of rotation of the furnace will be provided. The maximum and minimum limiting portions are provided by the pin 262 carried by the cam 257 engaging the ends of the arcuate slot 263 carried by the cam 256. After the desired adjustments have been made between the cam portions 256 and 257, as indicated by the graduations 259, the nut 261 is tightened up. Then the shaft 214 may be timed to zero or home position.

It is not necessary then to stop the motor while a furnace is being unloaded and reloaded and moved back into position but in order to start the burner the handle 267 turning the shaft 214 must be turned into home position. Therefore no matter what amount the cams 253 and 254 have been rotated away from home position during the cycle of furnace operations, these cams will occupy the position shown in Fig. 24 with relation to the lever 20 before the cycle of furnace operations can begin. The shaft 214 cannot be started automatically because it cannot be rotated by the motor through 360° of rotation. If the operator should forget to turn the shaft 214 to home position, the shaft 214 will be rotated clockwise as viewed in Fig. 24 until the cam 253 comes around and moves the finger 291 from the position shown in Fig. 24 to the position shown in Fig. 25 whereupon the projection 293 will move the pin 274 and the pawl 273 into inoperative position. Therefore although the cam 250 continues rotating, the shaft 214 can no longer be rotated until the operator turns this shaft manually into home position.

One of the important advantages of the present invention is that the turning off of the burner at the right time and the stopping of the furnace rotation after the furnace has cooled off sufficiently is entirely automatic and therefore the attention of an operator may be directed to the furnace only during the time of unloading and reloading the furnace.

A further advantage is that the operation of opening up the furnace, unloading the finished cylinder and reloading with a cylinder assembly is greatly simplified and can be easily done in less than a minute. The furnace controls are practically fool proof and therefore an inexperienced operator can operate these controls with safety. All that is necessary to do to start the furnace into operation is to turn the handle 267 clockwise until further motion is prevented. Where the normal operation of the furnace requires about 14 minutes it is possible for

one operator to attend 15 furnaces or five banks of three furnaces each. If in starting, the furnaces are loaded one minute apart, by the time the last furnace will be set into 5 operation the first one started will be completed. Therefore a cylinder will be completed every minute, and during each interval preceding the completion of a cylinder a furnace may be emptied and reloaded.

10 While the form of mechanism herein shown and described, constitutes a preferred form of embodiment of the present invention, it is to be understood that other forms might be adopted, all coming within the 15 scope of the claims which follow.

What I claim is as follows:

1. In a furnace, the combination with a shell member having one end closed and adapted to receive a body to be treated; 20 of a burner member adapted to project a flame into the open end of the shell member for heating the body; and means for moving one of said members in its entirety relatively to the other member to facilitate placing and removing the body into and out of position in the shell, respectively.

2. In a furnace, the combination with a shell for receiving a body to be treated; of a burner member adapted to project a 30 flame directly against the body in the shell for heating same; and means for moving the shell in its entirety from the burner to facilitate placing the body or removing same into or from the shell, respectively.

3. In a furnace, the combination with a shell for supporting a hollow body to be treated with its exterior walled off from the interior, said shell providing access from the outside to the interior of the body; of 40 a burner for supplying heat to the interior of said body; and means providing for retracting said shell from said burner to facilitate removal of said body.

4. In a furnace; the combination with a shell and a cover therefor, said shell and cover adapted to support a hollow body to be treated with its exterior walled off from the interior, said cover having an opening providing access to the interior of the body; of 50 a burner for supplying heat to the interior of the body; and means providing for retracting said shell from said burner to facilitate opening said cover and removing said body.

5. In a furnace, the combination with a shell for supporting a hollow body to be treated with its exterior walled off from the interior, said shell providing access from the outside to the interior of the body; of a 60 burner having a flame tube adapted to project through said burner and into said body; and means providing for retracting said shell from said tube to facilitate removal of said body.

6. In a furnace, the combination with a shell and a cover therefor, said shell and cover adapted to support a hollow body to be treated with its exterior walled off from the interior, said cover having an opening providing access to the interior of the body; 70 of a burner having a flame tube adapted to project through said burner and into said body; and means providing for retracting said shell from said tube to permit opening said cover and removal of said body. 75

7. In a furnace, the combination with a closed end shell member for receiving a body to be treated; of a burner member adapted to project a flame into the shell member for heating the body; means for moving one of 80 said members in its entirety, relatively to the other member to facilitate placing and removing the body into and from the shell respectively; and means for revolving the shell member. 85

8. In a furnace, the combination with a shell for supporting a hollow body to be treated with its exterior walled off from the interior, said shell providing access from the outside to the interior of the body; of a burner for supplying heat to the interior of 90 said body; and means providing for retracting said shell from said burner to facilitate removal of said body; and means for revolving said shell. 95

9. In a furnace, the combination with a shell for receiving and supporting a body to be treated of a burner including a horizontal flame tube projecting into said shell; means for rotating said shell about said 100 flame tube; and means providing for retracting said shell from said flame tube.

10. In a furnace, the combination with a shell for supporting a hollow cylindrical body to be treated with its axis horizontal; of a burner having a horizontal flame tube projecting into said body; means for rotating the shell about said flame tube; and means providing for retracting said shell 105 from said flame tube. 110

11. In a furnace, the combination with a shell for supporting a hollow body to be treated with its exterior walled off from the interior, said shell providing access from the outside to the interior of the body; of a burner having a horizontal flame tube projecting into said body; means for rotating the shell about the flame tube; and means providing for retracting said shell from said 115 flame tube. 120

12. In a furnace, the combination with a shell and a cover therefor, said shell and cover adapted to support a hollow body to be treated with its exterior walled off from the interior, said cover having an opening providing access to the interior of the body; of a burner having a horizontal flame tube projecting into said body; means for ro- 125

tating the shell about the flame tube; and means providing for retracting said shell from said flame tube.

13. In a furnace, the combination with a 5 rotatable shell for receiving a body to be treated; of a burner for supplying heat to said shell; means for rotating said shell including disengageable driving mechanism; and means providing for moving said shell 10 to connect or to disconnect said driving mechanism.

14. In a furnace, the combination with a rotatable shell for receiving a body to be treated; of a burner for supplying heat to 15 said shell; means for rotating said shell including disengageable driving mechanism; and means providing for retracting said shell from said burner and for causing the driving mechanism to be disengaged.

20 15. In a furnace, the combination with a shell rotatable about a horizontal axis for receiving a hollow body to be treated; of a burner having a horizontally disposed flame tube extending into said shell; means for 25 rotating said shell including disengagable driving mechanism; and means providing for retracting said shell from said burner and for causing the driving mechanism to be disengaged.

30 16. In a furnace, the combination with a shell rotatable about a horizontal axis for receiving a hollow body to be treated; of a burner having a horizontally disposed flame tube extending into said shell; means for 35 rotating said shell including an annular flange or track carried by said shell, and trunnions for receiving said track; and means providing for retracting said shell from said burner and for causing the track 40 to be withdrawn from the trunnions.

45 17. In a furnace, the combination with a shell and a cover therefor, said shell and cover adapted to support a hollow body to be treated with its exterior walled off from the interior, said cover having an opening 50 providing access to the interior of the body; said shell and cover being rotatable about a horizontal axis; of a burner having a horizontally disposed flame tube extending 55 into said shell; means for rotating said shell including an annular flange or track carried by said cover, and trunnions for receiving said track; and means providing for retracting said shell from said burner and for causing the track 60 to be withdrawn from the trunnions.

65 18. In a furnace, the combination with a shell having an opening and a burner for supplying heat through said opening; of means providing for moving the shell away from the burner so that its opening will face in a direction away from the burner.

19. In a furnace, the combination with a shell having an opening in one end which 70 fraces substantially horizontally; of a burn-

er for supplying heat through said opening; and means providing for moving the shell away from the burner so that the open end of the shell will face substantially vertically upward.

70

20. In a furnace, the combination with a shell and a cover therefor, said shell and cover adapted to support a hollow body to be treated with its exterior walled off from the interior, said cover having an opening 75 providing access to the interior of the body; of a burner for supplying heat through said opening in the cover; and means providing for moving the shell away from the burner so that the cover will face away from the 80 burner.

21. In a furnace, the combination with a shell and a cover therefor, said shell and cover adapted to support a hollow body to be treated with its exterior walled off from 85 the interior, said cover having an opening providing access to the interior of the body; said shell and cover being rotatable about a horizontal axis; of a burner for supplying heat through said opening in the cover; 90 and means providing for moving the shell away from the burner so that the cover will face substantially vertically upward.

22. In a furnace, the combination with a burner; of a shell having an opening 95 through which heat is received from the burner; of a carriage for rotatably supporting the shell; and means providing for moving said carriage so that the shell opening will face away from the burner.

100

23. In a furnace, the combination with a burner; of a shell having an open end through which heat is received from the burner; of a carriage for supporting the shell for rotation; means for rotating the 105 shell including disengageable driving connections; and means providing for moving said carriage so that the shell opening will face away from the burner and for disengaging said driving connections.

110

24. In a furnace, the combination with a burner having a flame tube; of a shell having an open end through which said flame tube extends into the shell; and means providing for moving said shell away from 115 said flame tube to clear the latter and to tilt the shell so that the shell opening faces away from the burner.

25. In a furnace, the combination with a burner having a flame tube; of a shell having an open end through which said tube extends into the shell; a shell carriage and a track for the carriage providing for movement of the shell to clear the tube; and means providing for tilting the carriage 120 relative to the track so that the shell opening will face away from the burner.

125

26. In a furnace, the combination with a burner having a flame tube; of a shell having an open end through which said tube 130

extends into the shell; a shell carriage and a track for the carriage providing for movement of the shell to clear the tube; and means providing for tilting the carriage 5 relative to the track and for supporting a portion of the weight of the shell and carriage.

27. In a furnace, the combination with a burner having a flame tube; of a shell having an open end through which said tube extends into the shell; a shell carriage and a track for the carriage providing for movement of the shell to clear the tube; and means for providing for tilting the carriage 10 relative to the track and for supporting a portion of the weight of the shell and carriage; and for limiting the tilting movement 15 of the carriage.

28. In a furnace, the combination with a burner having a flame tube; of a shell having an open end through which said tube extends into the shell; a shell carriage and a track for the carriage providing for movement of the shell to clear the tube; and 25 means providing a limit to the movement of the carriage on the track away from the burner and providing for tilting the carriage relative to the track as a moving force is thereafter applied to the carriage, and 30 then limiting further movement of the carriage away from the burner.

29. In a furnace, the combination with a burner and shell for receiving heat from the burner; of a shell carriage; a frame providing a track for the carriage; means providing for tilting the carriage with a portion 35 of the carriage load supported directly by the frame; and means for supporting the remainder of the carriage load as the carriage is tilted.

30. In a furnace, the combination with a burner and shell for receiving heat from the burner; of a shell carriage; a frame providing a track for the carriage; and means 45 providing a pivotal support for the carriage upon the frame after a portion of the carriage clears the track, the center of mass of the carriage load being so related to the pivotal support that the carriage will tilt by gravity with respect to the track.

31. In a furnace, the combination with a burner and shell for receiving heat from the burner; of a shell carriage; a frame providing a track for the carriage; and means 55 providing a stop limiting movement of the carriage along the track after a portion of the carriage has cleared the track, and providing a pivotal support for the carriage upon the frame after a portion of the carriage 60 clears the track, the center of mass of the carriage load being so related to the pivotal support that the carriage will tilt by gravity with respect to the track.

32. In a furnace, the combination with a burner and shell for receiving heat from the 65

burner; of a shell carriage; a frame providing a track for the carriage; and means providing a pivotal support for the carriage upon the frame after a portion of the carriage clears the track, the center of mass of the carriage load being so related to the pivotal support that the carriage will tilt by gravity with respect to the track; and means cooperating with the pivotal support in carrying the carriage load while permitting 70 the carriage to tilt due to gravity.

33. In a furnace, the combination with a burner and shell for receiving heat from the burner; of a shell carriage; a frame providing a track for the carriage; and means providing a stop limiting movement of the carriage along the track after a portion of the carriage has cleared the track, and means providing a pivotal support for the carriage upon the frame after a portion 80 of the carriage clears the track the center of mass of the carriage load being so related to the pivotal support that the carriage will tilt by gravity with respect to the track; and means cooperating with the pivotal support 85 in carrying the carriage load while permitting the carriage to tilt due to gravity.

34. In a furnace, the combination with a burner and shell for receiving heat from the burner; of a shell carriage; a frame providing a track for the carriage; and means providing a pivotal support for the carriage upon the frame after a portion of the carriage clears the track, the center of mass of the carriage load being so related to the pivotal support that the carriage will tilt by gravity with respect to the track; and means cooperating with the pivotal support 90 in carrying the carriage load while permitting the carriage to tilt due to gravity.

35. In a furnace, the combination with a burner and shell for receiving heat from the burner; of a shell carriage; a frame providing a track for the carriage; and means providing a stop limiting movement 95

of the carriage along the track after a portion of the carriage has cleared the track, and providing a pivotal support for the carriage upon the frame after a portion of the carriage clears the track, the center of mass of the carriage load being so related 100 to the pivotal support that the carriage will tilt by gravity with respect to the track; and means cooperating with the pivotal support in carrying the carriage load while permitting the carriage to tilt due to gravity; said means offering increased resistance to gravity as the tilting movement increases.

36. In a furnace, the combination with a burner and shell for receiving heat from the burner; of a frame providing a track; 110

120

125

a shell carriage movable on said track; means permitting movement of the carriage to a position adjacent the end of the track and then providing a pivotal support for 5 the carriage upon said frame, said means being located so that the carriage may swing about one end of the track; and means taking a portion of the carriage load as the carriage approaches the limit of travel toward said end of the track, and also permitting the swinging of the carriage and offering increased resistance as the swinging of the carriage from the track increases.

37. In a furnace, the combination with a 15 burner having a horizontal flame tube and shell located horizontally and receiving heat from said tube; of a frame providing a horizontal track; a shell carriage movable on said track; means permitting movement of 20 the carriage to a position adjacent the end of the track and then providing a pivotal support for the carriage upon said frame, said means being located so that the carriage may swing about one end of the track; and means taking a portion of the carriage load as the carriage approaches the limit of travel toward said end of the track, and also permitting the swinging of the carriage to a 25 portion with the axis of the shell substantially vertical; and offering increased resistance as the swinging of the carriage from the track increases.

38. In a furnace, the combination with a stationary burner having a flame tube; of 35 a furnace shell receiving said tube; a stationary stack including a portion adapted to extend into said shell to carry off combustion products; and means for retracting said shell from said stack and tube.

40 39. In a furnace, the combination with a stationary burner having a flame tube; of a stationary furnace stack having a portion extending along the tube and concentric therewith; a furnace shell having an open 45 end for receiving said tube and stack; and means for retracting said shell from said tube and stack.

40. In a furnace, the combination with a burner; of a furnace shell adapted to have 50 the burner flames injected therewith and movable in its entirety into and out of operative relation with the burner; and means for securing the shell in operative position.

41. In a furnace, the combination with a 55 burner; of a furnace shell retractable from the burner; means for latching the shell in operative position; and means for automatically unlatching the shell after a predetermined interval.

60 42. In a furnace, the combination with a burner; of a furnace shell retractable from the burner; means for latching the shell in operative position; and means for automatically unlatching the shell after a predetermined interval; and means for controlling

said automatic means to vary the interval.

43. In a furnace, the combination with a rotatable shell; of means for rotating said shell; and automatic means for discontinuing rotation of said shell after a predetermined interval. 70

44. In a furnace, the combination with a rotatable shell; of means for rotating said shell including disengageable driving connections; and automatic means for disengaging said driving connection after a predetermined interval. 75

45. In a furnace, the combination with a rotatable shell; of means for rotating said shell; and automatic means for discontinuing rotation of said shell after a predetermined interval; and means for controlling 80 said automatic means to vary the interval.

46. In a furnace, the combination with a rotatable shell; of means for rotating said shell including disengageable driving connections; and automatic means for disengaging said driving connections after a predetermined interval; and means for controlling 85 said automatic means to vary the interval. 90

47. In a furnace, the combination with a burner; of a rotatable furnace shell retractable from the burner; means for rotating said shell including disengageable driving connections, a portion thereof being carried 95 by the shell; and automatic means for retracting said shell from said burner after a predetermined interval to disengage said driving connections.

48. In a furnace, the combination with a 100 burner; of a rotatable furnace shell retractable from the burner; means for rotating said shell including disengagable driving connections, a portion thererof being carried 105 by the shell; means for latching said shell in operative position; and automatic means for unlatching said shell and for retracting said shell from said burner after a predetermined interval to disengage said 110 driving connections.

49. In a furnace, the combination with a burner; of a rotatable furnace shell retractable from the burner; means for rotating said shell including an annular track carried 115 by said shell, and trunnions for receiving said track carried by a stationary part; and automatic means for retracting said shell from said burner after a predetermined interval to disengage the said track from the trunnions. 120

50. In a furnace, the combination with a burner; of a rotatable furnace shell retractable from the burner; means for rotating said shell including an annular track carried 125 by said shell; and trunnions for receiving said track carried by a stationary part; means for latching said shell in operative position with the track engaging said trunnions; and automatic means for unlatching said shell; and for retracting said shell from 130

said burner after a predetermined interval to disengage said driving connections.

51. In a furnace, the combination with a shell and a liquid fuel burner; a source of liquid fuel; means for causing liquid fuel to be supplied to the burner including a source of compressed air; and temperature responsive means for stopping the supply of air under pressure to the burner.

10 52. In a furnace, the combination with a shell and a liquid fuel burner; a source of liquid fuel; means for causing liquid fuel to be supplied to the burner including a source of compressed air; a valve controlling the air; and electromagnetic means responsive to furnace temperature for causing said valve to close.

20 53. In a furnace, the combination with a shell and a liquid fuel burner; a source of liquid fuel; and means for causing liquid fuel to be supplied to the burner including a source of compressed air; a valve controlling the air supply manually operated means for opening said valve; and means responsive to furnace temperature for closing said valve.

30 54. In a furnace, the combination with a shell and a liquid fuel burner; a source of liquid fuel; means for causing liquid fuel to be supplied to the burner including a source of compressed air; a valve controlling the air; a spring tending to close the valve; manually controlled means for holding said valve open; and means responsive to furnace temperature for controlling said manual means whereby to permit said spring to close said valve.

40 55. In a furnace, the combination with a shell and a liquid fuel burner; a source of liquid fuel; means for causing liquid fuel to be supplied to the burner including a source of compressed air; a spring tending to close the valve; manually controlled means for holding said valve open; and electromagnetic means responsive to furnace temperature for controlling said manual means whereby to permit said spring to close said valve.

50 56. In a furnace, the combination with a burner and a rotatable shell; of means for rotating the shell; automatic means for stopping the burner; and automatic means for stopping rotation of the shell.

55 57. In a furnace, the combination with a burner and a rotatable shell; of means for rotating the shell; temperature responsive means for stopping the burner; and automatic means for stopping rotation of the shell after a predetermined interval.

60 58. In a furnace, the combination with a burner and a rotatable shell; of means for rotating the shell; temperature responsive means for stopping the burner; and automatic means for stopping rotation of the shell after a predetermined interval; and means for controlling said second automatic

means to vary the interval after which said automatic means operates.

59. In a furnace, the combination with a burner and a rotatable shell; of means for rotating said shell; means for controlling said burner including a valve and temperature responsive provisions for closing said valve; and automatic means for stopping shell rotation after a predetermined interval.

75 60. In a furnace, the combination with a burner and a rotatable shell; of means for rotating said shell including disengageable driving connections; temperature responsive means for stopping said burner; and automatic means for disengaging said driving connections after a predetermined interval.

80 61. In a furnace, the combination with a burner and a rotatable shell; of means for rotating said shell including disengageable driving connections; means for controlling said burner including a valve and temperature responsive provisions for closing said valve; and automatic means for disengaging said driving connections after a predetermined interval.

85 62. In a furnace, the combination with a burner and a rotatably and retractably mounted shell; means for rotating the shell including disengageable driving connections, a portion being connected to the shell; means for latching said shell in operative position with the driving connections engaged; temperature responsive means for stopping the burner; and automatic means for unlatching and for retracting said shell to disengage said driving connections after a predetermined interval.

90 63. In a furnace, the combination with a burner and a rotatably and retractably mounted shell; means for rotating the shell including disengageable driving connections, a portion being connected to the shell; means for latching said shell in operative position with the driving connections engaged; means for stopping the burner after a predetermined furnace temperature has been reached; automatic means for unlatching and for retracting said shell to disengage said driving connections after a predetermined interval; and means for controlling said automatic unlatching and retracting means whereby to vary the interval after said automatic means operates.

105 64. In a furnace, the combination with a burner and a rotatable shell; of means for rotating said shell; means for automatically stopping shell rotation after a predetermined interval; and manual means for controlling said automatic means whereby to permit starting rotation of the shell.

110 65. In a furnace, the combination with a burner and a rotatable shell; of means for rotating said shell including disengageable driving connections; means for automatically disengaging said connections after a

predetermined interval; and manual means for controlling said automatic means whereby to permit engagement of said driving connections to start rotation of the shell.

5 66. In a furnace, the combination with a burner and a retractable and rotatable shell; of means for rotating said shell including disengageable driving connections, a portion being connected to said shell; means for 10 latching said shell in position with the driving connections engaged; means for automatically unlatching said shell and for retracting said shell to disengage said driving connections; and manual means for controlling said automatic means whereby to permit latching of said shell in said operative position.

67. In a furnace, the combination with a burner and a retractable and rotatable shell; 20 of means for rotating the shell including rotating trunnions carried by a stationary part and an annular track carried by the shell; means for latching said shell in position with the track engaging the trunnions; means for automatically unlatching said shell and for retracting said shell to disengage the track from the trunnions; and manual means for controlling said automatic means to permit latching of said shell.

30 68. In a furnace, the combination with a burner and a rotatable shell; of means for rotating said shell including a motor rotating preferably at substantially constant speed, and disengageable driving connections between the motor and shell; and means for automatically disengaging said driving connections after a predetermined number of revolutions of said motor.

69. In a furnace, the combination with a 40 burner and a rotatable and retractable shell; of means for rotating said shell including a motor rotating preferably at substantially constant speed, and disengageable driving connections between the motor and shell, a portion being connected to said shell; means for latching said shell in position with the driving connections engaged; means for automatically unlatching said shell and for retracting said shell to disengage said driving 50 connections after a predetermined number of revolutions of said motor.

70. In a furnace, the combination with a burner and a retractable and rotatable shell; of means for rotating the shell including rotating trunnions carried by a stationary part and an annular track carried by the shell, and including a preferably constant speed motor; means for latching said shell in position with the track engaging the trunnions; means for automatically latching said shell and for retracting said shell to disengage the track from the trunnions after a predetermined number of revolutions of said motor.

65 71. In a furnace, the combination with a

burner and a rotatable shell; of means for rotating said shell including a motor rotating preferably at substantially constant speed, and disengageable driving connections between the motor and shell; means for automatically disengaging said driving connections after a predetermined number of revolutions of said motor; and manual means for controlling the automatic means to vary the number of revolutions of the motor and hence the time interval of furnace rotation.

72. In a furnace, the combination with a burner and a rotatable and retractable shell; of means for rotating said shell including a motor rotating preferably at substantially constant speed, and disengageable driving connections between the motor and shell, a portion being connected to said shell; means for latching said shell in position with the driving connections engaged; means for automatically unlatching said shell and for retracting said shell to disengage said driving connections after a predetermined number of revolutions of said motor; and manual means for controlling the automatic means to vary the number of revolutions of the motor and hence the time interval of furnace rotation.

73. In a furnace, the combination with a burner and a retractable and rotatable shell; of means for rotating the shell including rotating trunnions carried by a stationary part and an annular track carried by the shell, and including a preferably constant speed motor; means for latching said shell in position with the track engaging the trunnions; means for automatically latching said shell and for retracting said shell to disengage the track from the trunnions after a predetermined number of rotations of said motor; and manual means for controlling the automatic means to vary the number of rotations of the motor and hence the time interval of furnace rotation.

74. In a furnace, the combination with a burner and a rotatable shell; of means for rotating said shell including a motor rotating preferably at substantially constant speed, and disengageable driving connections between the motor and shell; means for automatically disengaging said driving connections after a predetermined number of revolutions of said motor; and manual means for controlling said automatic means whereby to permit engagement of said driving connections, and for setting said automatic means in initial position from whence, due to said amount of motion of the motor said automatic means moves to become operative as specified.

75. In a furnace, the combination with a burner and a rotatable and retractable shell; of means for rotating said shell including a motor rotating preferably at substantially

constant speed, and disengageable driving connections between the motor and shell, a portion being connected to said shell; means for latching said shell in position with the 5 driving connections engaged; means for automatically unlatching said shell and for retracting said shell to disengage said driving connections after a predetermined number of revolutions of said motor; and manual 10 means for controlling said automatic means whereby to permit engagement of said driving connections, and for setting said automatic means in initial position from whence, due to said amount of motion 15 of the motor said automatic means moves to become operative as specified.

76. In a furnace, the combination with a burner and a retractable and rotatable shell; of means for rotating the shell including 20 rotating trunnions carried by a stationary part an annular track carried by the shell; and including a preferably constant speed motor; means for latching said shell in position with the track engaging the trunnions; means for automatically latching 25 said shell and for retracting said shell to disengage the track from the trunnions after a predetermined number of revolutions of said motor; and manual means for controlling 30 said automatic means whereby to permit engagement of said driving connections, and for setting said automatic means in initial position from whence, due to said amount 35 of motion of the motor said automatic means moves to become operative as specified.

77. In a furnace, the combination with a burner and a rotatable shell; of means for 40 rotating said shell; means for automatically stopping shell rotation after a predetermined interval; manual means for controlling said automatic means whereby to 45 permit starting rotation of the shell, said manual means being operable to start the burner operating; and automatic means for stopping the burner.

78. In a furnace, the combination with a burner and a rotatable shell; of means for 50 rotating said shell including disengagable driving connections; means for automatically disengaging said connections after a predetermined interval; manual means for controlling said automatic means whereby 55 to permit engagement of said driving connections to start rotation of the shell, said manual means being operable to start the burner operating; and automatic means for stopping the burner.

79. In a furnace, the combination with a 60 burner and a retractable and rotatable shell; of means for rotating said shell including disengageable driving connections, a portion being connected to said shell; means 65 for latching said shell in position with the driving connections engaged; means for

automatically unlatching said shell and for retracting said shell to disengage said driving connections; manual means for controlling said automatic means whereby to permit latching of said shell in said operative position said manual means being operable to start the burner operating; and automatic means for stopping the burner. 70

80. In a furnace, the combination with a burner and a retractable and rotatable shell; 75 of means for rotating the shell including rotating trunnions carried by a stationary part and an annular track carried by the shell; means for latching said shell in position with the track engaging the trunnions; means for automatically latching said shell and for retracting said shell to disengage the track from the trunnions; manual means for controlling said automatic means to permit latching of said shell, said manual 80 means being operable to start the burner operating; and automatic means for stopping the burner. 85

81. In a furnace, the combination with a burner and a rotatable shell; of means for 90 rotating said shell including a motor rotating preferably at substantially constant speed, and disengageable driving connections between the motor and shell and means for automatically disengaging said driving connections after a predetermined number of revolutions of said motor; manual means for controlling said automatic means whereby to permit engagement of said driving 95 connections, and for setting said automatic means in initial position from whence, due to said amount of motion of the motor said automatic means moves to become operative as specified, said manual means being operable to start the burner operating; and automatic means for stopping the burner. 100

82. In a furnace, in combination with a burner and a rotatable and retractable shell; of means for rotating said shell including a motor rotating preferably at substantially 105 constant speed, and disengageable driving connections between the motor and shell; a portion being connected to said shell; means for latching said shell in position with the driving connections engaged; means for automatically unlatching said shell and for retracting said shell to disengage said driving connections after a predetermined number of revolutions of said 115 motor; manual means for controlling said automatic means whereby to permit engagement of said driving connections, and for setting said automatic means in initial position from whence, due to said amount of motion of the motor said automatic means moves to become operative as specified, said manual means being operable to start the burner operating; and automatic means for stopping the burner. 120

83. In a furnace, the combination with a 130

burner and a retractable and rotatable shell; of means for rotating the shell including rotating trunnions carried by a stationary part and an annular track carried by the shell; and including a preferably constant speed motor; means for latching said shell in position with the track engaging the trunnions; means for automatically latching the shell and for retracting said shell to disengage the track from the trunnions after a predetermined number of revolutions of said motor; manual means for controlling said automatic means whereby to permit engagement of said driving connections, and for setting said automatic means in initial position from whence, due to said amount of motion of the motor said automatic means moves to become operative as specified, said manual means being operable to start the burner operating; and automatic means for stopping the burner.

84. In a furnace, the combination with a heating means and a rotatable shell; of manually controlled means for starting shell rotation and automatically controlled means for stopping shell rotation.

85. In a furnace, the combination with heating means and a rotatable shell; of manually controlled means for starting shell rotation and for starting the burner; and automatically controlled means for stopping shell rotation.

86. In a furnace, the combination with heating means and a rotatable shell; of manually controlled means for starting shell rotation and for starting the burner; automatic means for stopping the burner; and automatically controlled means for stopping shell rotation.

87. In a furnace, the combination with a burner; of a shell heated by the burner; supporting means for providing for retracting the shell from the burner and for tilting the shell; and means for braking the retracting movement of the shell and for storing energy derived from the momentum of the shell, said means being adapted to give up said energy to assist in tilting the shell.

88. In a furnace, the combination with a burner; of a shell heated by the burner; supporting means for providing for retracting the shell from the burner and for tilting the shell; and means for braking the retracting movement of the shell and for storing energy derived from the momentum of the shell, said means being adapted to give up said energy to assist in tilting the shell, said means also adapted during the tilting of the shell away from the burner to cushion the fall thereof and to store energy which is used to assist in tilting the shell toward the burner.

89. In a furnace, the combination with a burner; of a shell heated by the burner;

supporting means providing for retracting the shell from the burner and for tilting the shell; and means for braking the retracting movement of the shell and for storing energy derived from the momentum of the shell, said means being adapted to give up said energy to assist in tilting the shell, said means also adapted during the tilting of the shell away from the burner to cushion the fall thereof and to store energy which is used to assist in tilting the shell toward the burner to cushion the fall thereof and to store energy which is used to assist in tilting the shell toward the burner to cushion the fall thereof and to store energy which is used to assist in starting the movement of shell toward the burner.

90. In a furnace, the combination with a burner and a support therefor including a substantially horizontal track; of a furnace shell; a shell carriage movable along said track and tilttable relative thereto when the carriage has been retracted a certain distance from the burner; and carriage braking and cushioning means including a spring, and a shock lever pivoted on said support and adapted to be moved by the shell carriage during the horizontal movement thereof away from the burner to compress said spring, said spring acting through said lever to assist in starting the tilting of the shell away from the burner.

91. In a furnace, the combination with a burner and a support therefor including a substantially horizontal track; of a furnace shell; a shell carriage movable along said track and tilttable relative thereto when the carriage has been retracted a certain distance from the burner; and carriage braking and cushioning means including a spring, and a shock lever pivoted on said support and adapted to be moved by the shell carriage during the horizontal movement thereof away from the burner to compress said spring, said spring acting through said lever to assist in starting the tilting of the shell away from the burner, said lever also adapted to be moved by the carriage during tilting thereof away from the burner to cushion the fall thereof, energy again being stored in said spring to be used in assisting the tilting of the shell toward the burner.

92. In a furnace, the combination with a burner; and a support therefor including a substantially horizontal track; of a furnace shell; a shell carriage movable along said track and tilttable relative thereto when the carriage has been retracted a certain distance from the burner; and carriage braking and cushioning means including a spring, and a shock lever pivoted on said support and adapted to be moved by the shell carriage during the horizontal movement thereof away from the burner to compress said spring, said spring acting through said lever

- to assist in starting the tilting of the shell away from the burner, said lever also adapted to be moved by the carriage during tilting thereof away from the burner to cushion the 5 fall thereof, energy again being stored in said spring to be used in assisting the tilting of the shell toward the burner, said lever also being engaged by the carriage during the tilting thereto toward the burner to cushion 10 the fall thereof onto the track, said spring again being compressed and energy stored therein to be used in assisting the horizontal movement of the carriage toward the burner.
- 15 93. In a furnace, the combination with a support including a track; of a furnace shell supported for movement along said track; and a burner associated with the furnace shell and adjustable with respect thereto.
- 20 94. In a furnace, the combination with a support including a track; of a furnace shell supported for movement along said track; a burner; and means for supporting the burner in positions of adjustment parallel to 25 said track.
- 25 95. In a furnace, the combination, with a support including a track; of a furnace shell supported for movement along said track; a burner; and means for supporting the burner in positions of adjustment normal to said track.
- 30 96. In a furnace, the combination with a support including a track; of a shell carriage movable along said track; and having a journal bearing; a furnace shell having a shaft loosely journaled upon said bearing so as to be tiltable thereto and said shell having a circular flange or track concentric to said shaft; and trunnions mounted for rotation 35 on axes parallel to said track, said trunnions having conical portions adjacent said circular flange, and the axes of the trunnions being so disposed that when the shell carriage is moved toward the trunnions the circular flange will be engaged by said conical portions thereby tilting the shell shaft with respect to its journal bearing and causing a portion of the shell weight to be carried by said trunnions.
- 40 97. In a furnace, the combination with a support including a track; of a shell carriage
- movable along said track; a furnace shell mounted for rotation upon said carriage and tilttable relative thereto; and means engaged by said shell upon a certain movement of the carriage along the track for tilting the said shell with respect to the carriage in order to take a portion of the shell load, said means producing rotation of the shell.
- 45 98. In a furnace, the combination with a burner having a flame tube; of a shell and cover therefor retractable from said burner, said cover having an opening for receiving the flame tube, said cover and shell having provisions for supporting a cylinder with one end thereof in communication with the cover opening and in such manner that the space within the shell and cover surrounding the cylinder is sealed off substantially 50 from the interior of the shell.
- 50 99. In a furnace, the combination with a burner having a flame tube; of a shell and cover therefor retractable from said burner, said cover having an opening for receiving the flame tube, said cover and shell having provisions for supporting a cylinder substantially concentric to said flame tube and surrounding a portion of the same, and in such manner that the space within the shell and cover surrounding the cylinder is sealed off 55 substantially from the interior of the shell.
- 55 100. In a furnace, the combination with a burner having a combustion chamber and a flame tube extending therefrom, and having a stack a portion of which surrounds said flame tube; of a shell having an opening in one end adapted to receive the stack and flame tube, said shell having provisions for supporting a cylinder with an open end 60 thereof adjacent the opening in the shell, and in such manner that the space within the shell surrounding the cylinder is sealed off substantially from the interior of the shell; and means for moving the shell toward the burner whereby a cylinder mounted within the shell will establish communication between the flame tube and stack.
- 65 In testimony whereof I hereto affix my signature.

CHARLES L. LEE.
